CARBURETOR

Aldo Curioni, Katonah, and Anthony Velo, White Plains, N. Y., assignors, by direct and mesne assignments, to Fuel-Saver Corporation

Application April 30, 1936, Serial No. 77,974

18 Claims. (Cl. 261—15)

This invention relates to carbureting devices for providing explosive mixtures to internal combustion engines, and more particularly relates to carburetors adapted for use in connection with gasoline or other liquid fuels possessing a fair degree of volatility, that is, fuels which can be converted into vapors by virtue of their own volatility or by the application of a relatively moderate amount of heat.

Automobile and aeroplane practice have steadily pointed out the desirability of admitting the fuel to an internal combustion engine under certain conditions which will improve its performance. For instance, it has been found advantageous to preheat the fuel in order to assist its vaporization before it reaches the cylinders, such preheating being especially advantageous in connection with the lower grades of gasoline and when cold weather prevails.

It has also been found desirable to add to the fuel air mixture a certain amount of water or preferably water vapor; and furthermore it has also been found advantageous to provide air filters in the path of the air supplied to the engine cylinders in order to prevent dust particles from reaching the inside of the engine and impairing its useful life.

In certain types of carburetors where provisions are made for assisting the vaporization of the fuel it is customary to cause the fuel to be sprayed into a current of heated air on its way to the cylinders; this system however, frequently fails to cause the gasoline to vaporize in its entirety, so that some particles of gasoline reach the cylinders in the liquid state; in certain other types of carburetors the gasoline is caused to come into more or less direct contact with electric heating elements, and this is likely to cause overheating and even pre-ignition in some extreme cases.

The primary object of this invention is to provide a novel and improved type of carburetor adapted to combine into one the advantage of supplying to the engine a preheated fuel-air mixture and that of adding to said mixture a certain amount of water vapor, at the same time insuring uniformity of performance both as to composition and temperature of the explosive mixture.

Another object is to provide a carburetor of a novel and relatively simple construction, adapted to supply both heated air and preheated vaporized fuel in order to form an explosive mixture, the air being also charged with water vapor and being entirely free of dust and other foreign matters.

A further object is to provide a novel and improved type of carburetor adapted to supply an explosive mixture of relatively uniform composition and temperature for the running of an internal combustion engine, said carburetor being also provided with means for supplying a mixture richer than normal for initiating the operation of the engine.

Other objects and advantages of the present invention will more fully appear as the description proceeds and will be set forth and claimed in the appended claims.

Our invention is illustrated by way of example in the accompanying drawing, in which:

Fig. 1 is a view in vertical section illustrating a carburetor embodying our invention; and

Fig. 2 is a horizontal section through line 2—2 of Fig. 1.

Referring to said drawing, 10 designates the body of the carburetor which is hollow to form a chamber 11. The power part of said chamber contains a body of water 12 which can be admitted thereto through an inlet 12'. The level of said body of water reaches about half way the height of chamber 11 as indicated by line a—a, and is maintained at said level in any suitable or well known manner.

Within chamber 11 is provided a receptacle 13, preferably annular in form, having an annular chamber 14 designed to carry a certain amount of gasoline in its lower part, the level of the gasoline being indicated by line b—b. The bottom 15 of receptacle 13 is in contact with the body of water 12 contained within chamber 11, and the height of said receptacle 13 is such as to leave an air space 16 between its top 17 and the top 18 of chamber 11. Receptacle 13 is disposed concentrically to chamber 11 and is smaller in diameter than said chamber so that there will be an annular space 19 separating the outer surface of receptacle 13 from the surface of chamber 11.

The upper part of chamber 11 is formed with a lateral outlet 20 communicating with a downwardly directed conduit 21 having its lower end bent to form a laterally directed extension 22. At its upper end said conduit 21 is provided with an outlet 23, which constitutes the discharge outlet of the carburetor, leading to the intake manifold of the engine. A pipe 24 is provided centrally of chamber 11, said pipe projecting downwardly through top 18 and having its lower end 25 opening at a point somewhat above the bottom 26 of chamber 11, the upper end of said pipe

extending a certain distance above top 18 and carrying a rotatable valve member 27 controlled through an arm 28 extending therefrom.

Said valve member is provided with openings

29 adapted to be set in register or out of register with ports 30 provided through the side of the upper end of pipe 24, said openings being provided for the purpose of regulating the area of the air inlet. At some point intermediate its length or preferably at its lower end said pipe 24 is provided with a filtering wall made of fine mesh wire fabric. For instance, in the drawing, the lower end 25 of pipe 24 is shown provided with a removable cap 31, the disk portion of which is formed by a piece of wire fabric 32. The diameter of opening 33 provided in the center of receptacle 31 is greater than the diameter of pipe 24, so that an annular passage 34 will be formed between the inner surface of opening 33 and the outer surface of pipe 24. The top of an annular chamber 14 is provided with an outlet pipe 35 extending upwardly therefrom and leading to outlet 20. Suitable means are provided for heating the water contained within chamber 11. For instance, at the bottom of said chamber may be provided electric heating elements 36, 37, encased within shells 38, 39, said elements being energized by means of any suitable available source of electric current, for instance, the battery or the ignition system of a motor car, and being automatically governed by any suitable thermostatic appliance (not shown) which may in its turn be controlled by the temperature of the water 12 within chamber 11.

At some point below the level of the body of water 12, chamber 11 is preferably provided with filtering and/or delaying elements, such as represented for instance by a filtering wall 40 consisting of fine mesh wire fabric and baffle plates

41, 42. The elements so far mentioned already constitute an operative organization embodying the basic inventive idea, which resides mainly in using the temperature of the body of water 12 as the agent assisting the vaporization of the fuel, at the same time using said water as the agent for preheating the air going with said fuel to form the explosive mixture and for charging said air with water vapor; incidentally also using the water as a means for freeing the air of dust and other impurities.

As will be readily understood, assuming that there be an open and continuous connection between outlet 20 and outlet 23, the suction produced by the engine pistons through outlet 23 will cause air to be drawn within chamber 11 through pipe 24, said air being discharged within the body of water 12 at the lower end of said pipe and reaching the upper part of chamber 11 by bubbling through the body of water and passing through passages 19, 34. At the same time a suction will also be produced within pipe 35, causing fuel vapors to be discharged by said pipe within the current of air streaming through outlets 20, 23.

Since water 12 is normally maintained at a relatively high temperature, the air passing through it will absorb and carry off some of the heat; furthermore, the gasoline within chamber 14 will also acquire the temperature of the water due to the direct contact between the bottom 15 of chamber 14 and said water, and will therefore readily vaporize. By virtue of this arrangement, the air and fuel streams issuing through outlet 20 and pipe 35 will be in a preheated condition and will readily mix to form an explosive mixture discharged through outlet 23. Further-

more, the fuel vapors will be entirely free of liquid particles, and the air will be charged with a certain amount of water vapor generated by the warm water.

The arrangement described results in several advantages which have considerable practical importance. To begin with, the arrangement is of the utmost simplicity and makes possible an easy regulation of the fuel contents of the explosive mixture through the regulation of the temperature of the body of water and through the control of the amount of air admitted through valve 27. As a rule a higher temperature of the water will tend to produce a richer mixture, due not only to the fact that the evaporation of the fuel will take place in a more energetic manner, but also to the fact that the air heated at a higher temperature will have a higher vapor saturation point.

It will be observed that the air discharged within the body of water must pass through filtering wall 40 and must follow a sinuous passage defined by the baffle plates 41, 42, before it can issue into the space above the water, so that said air is broken up in bubbles which altogether will have a large surface of contact with the surrounding water and will therefore more readily absorb both heat and water vapor. Furthermore, the air passing through filtering wall 40 and also through a filtering wall such as 32, will thereby be freed of all foreign matter, which will eventually collect at the bottom of chamber 11 and above filtering wall 32. It is therefore seen that a single agent, which is the body of warm water 12, provides means for assisting the vaporization of the fuel, producing a preheated explosive mixture, supplying water vapor to said mixture and purifying the air supplied to said mixture.

The carburetor shown in the drawing includes certain other elements that we will now describe. As will be readily understood, some suitable means must be provided in order to maintain the fuel within chamber 14 at a predetermined level. To this end, in the drawing we show a fuel supply pipe 43 admitting fuel to chamber 14, the flow of said fuel being controlled by a needle valve 44. Within chamber 14 is provided a quasi-annular float 45, having an outwardly extending bracket 46 pivotally mounted on a rod 47 extending across a peripheral segmental portion of chamber 14.

Said bracket 46 is provided with a lug 48, which upwardly extends to engage valve 44 and which forces said valve to its closed position when the fuel within chamber 14 reaches its normal level, as shown. When, through vaporization of the fuel its level within chamber 14, decreases, the float 45 will gradually tilt downwardly, causing lug 48 to retract the needle valve, allowing some new fuel being admitted to the chamber, up to such point when normal level will have been re-established.

In view of the fact that a particularly rich mixture should be provided when the engine is started, under certain conditions it may be desirable to use the carburetor described for the normal running of the engine and to make special provisions for starting. Conduit 21 extending from outlet 20 is provided for this specific purpose, its lateral extension 22 forming a passage for the air and a pipe 49 leading from annular chamber 14 to the inside of conduit 21. Said pipe terminates in a nozzle 50, constituting the spray nozzle for the fuel when, upon starting, the explosive mixture is formed by causing a suction

within conduit 21 so as to draw air through passage 22 and fuel in the form of a spray through nozzle 50. In order to shift the operation from this auxiliary carburetor to the main carburetor previously described and vice versa, we provide a valve 51 pivotally mounted at 52 at a point where said valve can tilt between the position shown in full lines where said valve closes outlet 20 and outlet 23 communicates with conduit 21 and the position shown in dotted lines at 51' where conduit 21 is closed and communication is established between outlet 20 and outlet 23.

Said valve is automatically controlled by a thermostatic element 53 within chamber 11, said thermostatic element being in contact with the water 12 and having its free end 54 connected by a link 55 with valve 51. Said thermostatic element is designed so as to tend to straighten out and eventually assume a curvature in the direction opposite to that shown when the water reaches a certain temperature, so that, as a consequence, when the motor is started the auxiliary carburetor will function, but as soon as the water within chamber 11 becomes sufficiently warm the auxiliary carburetor will cease to function and the main carburetor will take its place.

It is to be understood that in order to carry our invention into practice, it is not absolutely necessary that an auxiliary carburetor be provided in unitary form with the main carburetor, since it is possible to use an ordinary carburetor for starting the engine and to shift the operation from one carburetor to the other by hand, if an auxiliary carburetor should be found necessary. As a matter of fact, when the heating of the water within chamber 11 can be effected without depending up on the operation of the engine when starting, it becomes possible to use the carburetor at all times without the assistance of an auxiliary carburetor for starting.

At times it may be desirable to partially or totally supply air directly to the air space 18 above the water without causing said air to pass through the body of water itself. To this end another valve 56 can be provided within pipe 24, said valve being rotatable so as to bring its openings in or out of the register with ports 57 through the wall of the pipe. By operation of said valve it thus becomes possible to control the amount of water vapor supplied to the explosive mixture because that part of the air which will be supplied directly to the air space 18 will naturally take up much less water vapor than the air which is caused to bubble through the body of water itself.

It may also be desirable to obtain a richer mixture by causing part of the air to first pass and bubble through the body of liquid fuel before it is delivered to the explosive mixture, and to this end another pipe 58 may be provided having its lower end extending within the body of fuel and its upper end upwardly projecting at 59 from the top of chamber 11, said upwardly projecting portion carrying a valve 60 controlling ports 61, said valve being actuated by means of a controlling arm 62. The bottom 20 of chamber 11 may be provided with an opening 63 directly opposite pipe 24, said opening being normally closed by a screwed cap 64 and giving access to the inside of chamber 11 for removing any sediment that should be collected therein.

Said opening 63 is preferably larger in diameter than pipe 24, as shown, so that cap 64 can also be removed through said opening for cleansing purposes. It will be observed that in the device illus-

trated, we provide a chamber for holding the fuel which is entirely independent of, and separate from the water containing chamber. We do this because of the greater ease with which the respective levels of the two liquids can be maintained, but it is within the scope of our invention to have the fuel resting directly on top of the water, so that the air may bubble through both the water and fuel, the separation between the two liquids being automatically effected by virtue of the difference in their specific gravities.

The constructional details of the device can vary from those shown without departing from the inventive idea; the drawing should therefore be understood as being intended for illustrative purposes only and not in a limiting sense. We accordingly reserve the right to carry our invention into practice in all those ways and manners which may enter, fairly, into the scope of the appended claims.

We claim:

1. In a carburetor for internal combustion engines having a suction conduit, a receptacle partially filled with water, having its upper part provided with an outlet adapted for connection to said suction conduit, means for heating said water, a body of liquid fuel in a heat exchanging relation to said water, and an air conduit having its inlet communicating with the open air and having its outlet submerged within said body of water.

2. In a carburetor for internal combustion engines having a suction conduit, a receptacle partially filled with water, having its upper part provided with an outlet adapted for connection to said suction conduit, means for heating said water, a body of liquid fuel in a heat exchanging relation to said water, an air conduit having its inlet communicating with the open air and having its outlet submerged within said body of water, and means for regulating the area of the air inlet.

3. In a carburetor for internal combustion engines having a suction conduit, a receptacle partially filled with water having its upper part provided with an outlet adapted for connection to said suction conduit, a container having a chamber partially filled with liquid fuel, within said receptacle in a position to absorb heat from said water, said container leaving air passages between its surface and the surface of said receptacle and having the upper part of its chamber provided with a tubular outlet member leading to said outlet, means for heating said water, and an air conduit having its inlet communicating with the open air and having its outlet submerged within said body of water.

4. In a carburetor for internal combustion engines having a suction conduit, a receptacle partially filled with water having its upper part provided with an outlet adapted for connection to said suction conduit, a container having a chamber partially filled with liquid fuel, within said receptacle in a position to absorb heat from said water, said container leaving air passages between its surface and the surface of said receptacle and having the upper part of its chamber provided with a tubular outlet member leading to said outlet, means for heating said water, an air conduit having its inlet communicating with the open air and having its outlet submerged within said body of water, and means for filtering the air sucked through said air conduit before it reaches said outlet.

5. In a carburetor for internal combustion

5. between its surface and the surface of said receptacle and having the upper part of its chamber provided with a tubular outlet member leading to said outlet, means for heating said water, an air conduit having its inlet communicating with the open air and having its outlet submerged within said body of water, and means for maintaining the fuel within said container at a predetermined level.
10. 14. In a carburetor for internal combustion engines having a suction conduit, a receptacle partially filled with water having its upper part provided with an outlet adapted for connection to said suction conduit, a container having a chamber partially filled with liquid fuel, within said receptacle in a position to absorb heat from said water, said container leaving air passages between its surface and the surface of said receptacle and having the upper part of its chamber provided with a tubular outlet member leading to said outlet, means for heating said water, an air conduit having its inlet communicating with the open air and having its outlet submerged within said body of water, means for regulating the area of the air inlet, means for admitting air directly to the space within said receptacle above the level of the water therein contained, and means for admitting air to the fuel within said container.
15. 15. A carburetor for internal combustion engines having a suction conduit, comprising a receptacle partially filled with water, having its upper part provided with an outlet adapted for connection to said suction conduit, means for heating said water, a body of liquid fuel in a heat exchanging relation to said water, an air conduit having its inlet communicating with the open air and having its outlet submerged within said body of water, an additional carburetor of the fuel spray nozzle type also adapted for connection to said suction conduit, and means for selectively connecting said suction conduit to either carburetor.
20. 16. A carburetor for internal combustion engines having a suction conduit, comprising a receptacle partially filled with heated water, having its upper part provided with an outlet adapted for connection to said suction conduit, a body of liquid fuel in a heat exchanging relation to said water, an air conduit having its inlet communicating with the open air and having its outlet submerged within said body of water, an additional carburetor of the fuel spray nozzle type also adapted for connection to said suction conduit, and thermostatically controlled means for selectively connecting said suction conduit to either carburetor.
25. 17. In a carburetor for internal combustion engines having a suction conduit, a receptacle partially filled with water, having its upper part provided with an outlet adapted for connection to said suction conduit, a container having a chamber partially filled with liquid fuel and having a vapor space above said fuel, also adapted for connection to said conduit, an air intake tube having its outlet submerged in said body of water, and an air intake tube having its outlet submerged in said body of liquid fuel.
30. 18. In a carburetor for internal combustion engines having a suction conduit, a receptacle partially filled with heated water having its upper part provided with an outlet adapted for connection to said suction conduit, a container having a chamber partially filled with liquid fuel and having the upper part of its chamber provided with an outlet also leading to said suction conduit, said fuel container being in a heat exchanging relation to the water contained in said receptacle, and means for supplying air to said receptacle so as to cause said air to become charged with water vapor before reaching the outlet thereof.

ALDO CURIONI.
